UNITED STATES PATENT OFFICE.

JOHN BOWSER, OF MARION, VIRGINIA, ASSIGNOR OF PART TO JOHN W. RICHARDSON, GEORGE W. RICHARDSON, GEORGE W. PRATT, AND J. L. THORNTON, ALL OF SAME PLACE.

RAILWAY-GATE.

SPECIFICATION forming part of Letters Patent No. 406,387, dated July 2, 1889.

Application filed April 19, 1889. Serial No. 307,711. (No model.)

To all whom it may concern:

Be it known that I, JOHN BOWSER, a citizen of the United States, residing at Marion, in the county of Smyth and State of Virginia, 5 have invented a new and useful Railway-Gate, of which the following is a specification.

This invention has relation to railway-gates, the object being to provide a gate and mechanism for operating the same, so as to close 10 the gate at the approach of a train and open the same after the train has passed.

The invention consists in certain features of construction and combination of parts, hereinafter specified, and more particularly 15 pointed out in the claims.

Referring to the drawings, Figure 1 is a perspective view of a railway-gate provided with my improved mechanism. Fig. 2 is a plan view. Fig. 3 is a detail in perspective 20 of one of the spring-treads. Fig. 4 is a side elevation of the gate and its operating mechanism, and Fig. 5 is a detail hereinafter described.

Like numerals of reference indicate like 25 parts in all the figures.

If desired, I may duplicate the gate at the other side of the track, the only requisite being that a suitable connecting mechanism be employed, the gate-actuating mechanism 30 hereinafter specified serving to operate both gates.

1 represents an ordinary railroad-track, at the side, or it may be at the sides, of which and at a crossing there is located a longitudinal beam or base 2. At one end of the beam are arranged inclined uprights 3 at each side of the beam, and at the opposite end a post 4, the upper end of which is transversely slotted, as at 5. Between the upright 3 and post 35 5 upon the beam 2 is located a bifurcated post or standard 6; or, if desired, an equivalent space may be formed by the arrangement of opposite posts. Diagonal bars 7 extend from the center post 6, and are secured at their upper ends to the upper ends of the inclined uprights 3.

8 represents the gate-bar, which is pivoted at 9 to the intermediate post 6 within the bifurcations thereof, the outer end of the bar 50 being designed to extend across the space be-

tween the posts 6 and 4 and to rest in the bifurcation 5 of the latter post. The rear end of the bar 8 is weighted at 10, so that if not otherwise influenced the bar would be maintained in a vertical position.

55

Pivoted at 11 in the diagonal braces 7, and above the bar 8, is a rock arm or lever 12, having a central upwardly-extending arm 13 and a rear shorter arm 14. The lever 12 is connected by a link 15 to the gate-bar 8 in 60 rear of its pivot 9, and from the rear end of the arm 14 of the lever there depends a loose rod 16, the lower end of which is journaled in a pivoted arm 17, secured to the base 2.

18 represents a curved spring-tread, which 65 is arranged upon the sides of the rails 1, and consists of the central thickened portion 19, having a central depending arm 20, provided with a laterally-projecting pin 21 and the opposite reduced spring portions 22, the ends of 70 the tread being flattened and provided with elongated slots 23. Through these slots are passed bearing-pins 24, the ends of which enter the rails. (See Figs. 2 and 5.)

Upon a tie or other base 25, projecting from 75 one side of the track, there is mounted a rock-shaft 26 in bearings 27. The inner end of the shaft is provided with a rock-arm 28, having an elongated slot 29 at its free end, which takes over the laterally-projecting pin formed 80 on the depending arm of the spring-tread. The opposite end of the rock-shaft 26 is provided with a longer arm 30, which extends upwardly and into a plane with the base 2.

Pivoted to the intermediate post 6 is a latch 85 31, to the lower end of which is pivoted a connecting-rod 32, the opposite end of which is loosely connected with the rock-arm 30, said connecting-rod acting to actuate the latch. The latch is arranged in the path of a projecting pin 33, extending from the gate-bar 8, and is adapted to retain the gate-bar in a closed position, the latch being under a normal tension furnished by the spring-tread and communicated through the rock-shaft, its 90 rock-arms, and the connecting-bar described. Beyond the crossing I locate a second or closing tread 34, the same being similar in construction to the first-mentioned tread and consisting of the thickened portion 34^a, having 95 100

a central depending arm 45, the opposite reduced portions 46, and the slotted ends 47.

Upon a base 35 is mounted a rock-shaft 36 in bearings 37, said shaft terminating in bent 5 rock-arms 38 and 39, the former being slotted at 40 to receive the laterally-extending pin 49 on the central arm of the spring-tread, and the opposite rock-arm extending upwardly, and by a wire or other connecting means 41 10 being connected to the arm 13 of the lever 12. (See Figs. 1 and 3.)

A train approaching first comes in contact with the spring-tread last described, which may be arranged at any distance from the 15 crossing, and the drive-wheels of the locomotive, striking the tread, depress the same against the tension of its springs and oscillate the rock-shaft 36, drawing the rock-arm 39 to the rear. This in turn draws upon the 20 wire 41, and through the medium of the arm 13 the lever 12 is raised, and from thence the strain is communicated to the rear end of the gate-bar 8 and the gate is closed. The wheels of the locomotive now come in contact with 25 the gate-opening spring-tread 18 and compress the same, oscillating the rock-shaft and its rock-arms, the outer one of which rock-arms 26 draws the connecting-rod 32, which in turn draws upon the lower end of the latch, 30 and serves to disconnect the same from the projecting pin with which the gate-bar 8 is provided. This permits the weight 10 to raise the gate to a vertical or open position.

The tread 34 is duplicated at the opposite 35 side of the crossing where the track is single, and in that case, to prevent a departing train from closing the gate after it has passed by the crossing by coming in contact with the tread 34, I bend that end of each tread which 40 is nearest the gate, as at 41^a, so that the flange of the wheel of the departing train will enter between the rails and the spring-tread and force the same laterally upon its bearing-pins away from the rails. To permit this lateral 45 movement upon the pins, I insert between the head of the pins 42 a washer 43 and a coiled spring 44, which serves to return the spring-tread after the train has passed to a position adapted to be operated by a train coming in 50 the opposite direction.

The opposite companion spring-tread is provided with a duplicate rock-shaft 36 and rock-arms, to the outer one of which is connected the lower end of the pivoted arm 17 by 55 means of a connecting wire or rod 46, extending under the base 2.

Having thus described my invention, I claim—

1. The combination, with the rail 1, having the laterally-projecting pins 42, of the spring-tread 34, having the central thickened portion 34^a, the offsetted portion 41^a, and the reduced intermediate spring portions 46, terminating in slots 47 and mounted on the pins, substantially as specified. 60

2. The combination, with the rail 1, having the projecting pins 42, terminating in heads, of the tread 34, having the intermediate spring portions 46, slotted ends 47, mounted on the pins, the intermediate outwardly- 70 curved portion 41^a, and the coiled springs 44, interposed between the heads and the tread, substantially as specified.

3. The combination, with the gate-frame provided with a gate, and a latch adapted to 75 operate upon a pin projecting from the gate, of a connecting-rod, as 32, a rock-arm connected with the rod and mounted upon a rock-shaft provided with an opposite slotted arm, and a spring-tread pivoted to the rail and 80 connected with the rock-arm, substantially as specified.

4. The combination, with the signal-frame, of a gate pivoted therein, a three-armed lever pivoted in rear of the gate and having the 85 front one of its arms connected therewith, oppositely -arranged spring-treads, each of which is connected to one of its remaining arms and adapted to operate the same to close the gate, and an intermediately-arranged 90 spring-tread adapted to operate a rock-shaft for releasing the gate, substantially as specified.

5. The combination, with the rail 1, provided with the opposite treads 34, rock-shafts 95 36, and rock-arms 39, of the gate-frame having the pivoted gate, the lever 12, mounted in rear of the gate and having arms 13 and 14, the rod 41, connecting the arm 13 and the rock-arm of one of the shafts 36, a rod 16, connecting the arm 14 to a pivoted arm 17, and the rod 46, connecting the lower end of the arm 17 to the opposite rock-arm 36, substantially as specified. 100

In testimony that I claim the foregoing as 105 my own I have hereto affixed my signature in presence of two witnesses.

JOHN BOWSER.
